Patented Apr. 18, 1916.

George Goddu

UNITED STATES PATENT OFFICE.

GEORGE GODDU, OF WINCHESTER, MASSACHUSETTS, ASSIGNOR TO UNITED SHOE MACHINERY COMPANY, OF PATERSON, NEW JERSEY, A CORPORATION OF NEW JERSEY.

MACHINE FOR ATTACHING WELTS TO SHOES.

1,179,821.

Specification of Letters Patent. Patented Apr. 18, 1916.

Application filed August 19, 1915. Serial No. 46,280.

To all whom it may concern:

Be it known that I, GEORGE GODDU, a citizen of the United States, residing at Winchester, in the county of Middlesex and State 5 of Massachusetts, have invented certain Improvements in Machines for Attaching Welts to Shoes, of which the following description, in connection with the accompanying drawings, is a specification, like reference characters 10 acting on the drawings indicating like parts in the several figures.

This invention relates to machines for attaching welts to shoes in which a welt, or strip of leather, is secured to the underside 15 of the insole by separate fastenings which are driven directly through the welt, upper, and insole.

Welts as now frequently constructed are made of soft thin leather which before being 20 attached to the shoe is usually moistened or tempered, and when metallic fastenings are driven into the welt to secure the welt, upper, and insole together, the head portions of the fastenings are liable to sink into the 25 material of the welt or penetrate it so such an extent as to insecurely fasten it to the other shoe parts, so that during manufacture or subsequent wear the welt is liable to pull off or become detached from the shoe. 30 This is particularly liable to occur while the fastenings are being driven by reason of the driving energy of the inserting mechanism, which must be sufficient to completely drive the fastening into the welt, upper, and insole, and in some cases to draw the penetrating end of the fastening by driving it 35 back into the insole. This may not be removed even where an opening is made through or partly through the welt, upper, 40 and insole to receive the fastening, because the head of the fastening must be driven into firm holding relation with the welt surface against which it bears.

An important feature of the present invention, therefore, consists in directing along with and on to the welt as it is presented to the fastening inserting position a 45 separate welt reinforcing strip to support the head of a fastening and prevent it penetrating the welt when the fastening is driven.

The welt being of pliable and soft leather is liable to curl or roll over as it is laid or

bent about the toe and shank of a shoe and cause misplacement of the welt or reinforcing strip or both relative to the edge of the 55 insole and upper, and another important feature of the invention consists in supporting the outer edge of the welt where it projects beyond the shoe, and guiding the welt and reinforcing strip to the fastening inserting position with their inner edges in substantially the same vertical plane.

The invention comprises various other additional features and combinations of parts, as well as certain details of construction which will hereinafter more fully appear and be clearly defined by the claims.

Referring to the accompanying drawings which illustrate a good practical form of the invention:—Figure 1 is a view in front elevation of the upper or head portion of a fastening inserting machine for attaching welts to lasted shoes and embodying the present invention, some of the parts being broken away; Fig. 2 is a perspective detail on an enlarged scale showing more particularly the relation of the guides for the welt and welt reinforcing material and the fastening inserting mechanism adjacent the fastening inserting position; Fig. 3 is a side elevation looking from the right of the machine and showing more particularly the guides for the welt and reinforcing material, the roll for supporting the projecting edge of the welt, the horn, and adjacent parts; Fig. 4 is a perspective view of the guides detached showing the preferred manner of association and relative adjustment; Fig. 5 is a vertical sectional view from front to rear of the machine showing the relation of parts at the 80 fastening inserting position; Fig. 6 is a view 85 showing part of a lasted shoe supported upon a work support or horn and the relation of the welt reinforcing strip, welt, upper, insole, and the fastenings securing the 90 parts together.

So far as the broader features of the invention are concerned the fastenings for attaching the welt to the insole may be of any suitable character and may be supplied to 100 the fastening inserting mechanism from a hopper containing loose fastenings in bulk, or the fastenings may be made in the machine which inserts or drives them into the

shoe, but in the illustrated machine the fastenings are supplied from a hopper to the inserting mechanism through a chute or raceway, substantially as in Letters Patent 5 granted L. Goddu, No. 490,624, January 24, 1893.

As illustrated, the machine comprises a column 1 on which is mounted the head frame 2 for supporting the fastening inserting mechanism and its operating means. The form and character of the fastening inserting mechanism may vary according to the kind of fastening to be inserted into the shoe by it, and in the present instance it 10 comprises a movable head 3 in which is mounted a driver bar 4 carrying a driver 5, and an awl bar 6 carrying an awl 7. A disk 8 actuated from the main driving shaft 9 is provided with a lug 10 for lifting the driver bar and driver, the fastening inserting stroke of which is made by an arm 11 mounted in the bracket 12 and normally under the influence of a strong spring 13. The actuating force of the spring is delivered 15 to the driver bar through the link 14, the construction being such that the driver bar will be raised by the lug 10 on the disk 8 and then freed to the action of the spring 13, substantially as in the patent mentioned for driving the fastening into the work supported upon the work supporting horn 15.

In the illustrative machine an opening is formed in the work for the reception of a 20 fastening by means of the awl 7 which passes through the throat block 16 and is actuated to form such opening by a toothed segment 17 carried by an arm 18 secured to a rock shaft 19 actuated by suitable cam means on the main driving shaft as in the 25 said patent. When the awl is in the work it is moved to feed the work over the horn for the insertion of the next fastening by rocking movement of the head 3, which, as described in said patent, may be secured by an 30 operating or feed arm 20 carried by a rock shaft mounted in the head frame 2 and suitably actuated from the main driving shaft. The rocking head 3 is operatively connected 35 to the arm 20 by a pin 21 and block 22, the construction being such, as more fully disclosed in said patent, that upon rocking movement of the feed arm 20, the awl will effect feed movement of the work over the 40 horn for the insertion of the next fastening.

The fastenings may be supplied to the inserting mechanism by means of a raceway 23, and in order to deliver the fastening singly to the inserting mechanism a separator is carried by an arm 24 pivotally mounted at 25 and actuated by a suitable cam and spring as in the Goddu patent mentioned.

Secured to the head frame 2 is the stationary guiding means for separately directing

the welt and the welt reinforcing material 65 or strip to the fastening inserting position.

In the present instance the guiding means comprises an arm 26 provided with elongated slots 27 through which pass the bolts 28 for adjustably securing the guiding 70 means to the head frame 2, as indicated in Figs. 2 and 3. The arm 26 is provided with a head portion 29 provided with a passageway 30 for the welt 31, the construction being such that the welt may be directed 75 through the passageway to the fastening inserting position above the insole and overlying edge of the upper of the lasted shoe sustained upon the work supporting horn 15, as indicated in Figs. 5 and 6. By adjustment of the arm 26 on the head frame the welt may be directed to the fastening inserting position in desired relation with the edge of the insole to secure insertion of fastenings into the welt, upper and insole to 80 properly unite the parts, and provide a projecting outer edge portion of the welt for securing the outsole thereto.

The action of the fastening inserting mechanism in driving metallic fastenings to 90 unite the welt, upper, and insole is liable to cause the heads of the fastenings to penetrate the welt, or pass so far below its surface that the welt may not be properly united to the other shoe parts. This is particularly liable to occur when a welt of soft, thin leather is used and the welt has been put in temper. The present invention overcomes this objectionable condition by separately directing along with the welt a welt 100 reinforcing strip, which overlies the fastening receiving portion of the welt and supports the head of the fastenings under the blows of the fastening inserting mechanism, and prevents the heads of the fastenings 105 from penetrating the welt itself. The reinforcing strip is preferably formed of material through which the heads of the fastening will not readily pass as they are driven, such as canvas, tape, or the like.

In the present instance, the welt reinforcing strip is carried upon a reel or spool 110 rotatably mounted upon a bracket 33 projecting from the head frame of the machine from which it is drawn by the feed of the 115 work. Above and separate from the passageway for the welt in the guiding means, is another passageway for the welt reinforcing strip. These separate passageways or guides for the welt and reinforcing strip 120 may be variously formed. In the illustrated instance of the invention the head 29 has adjustably secured thereto an arm 34 having a head 35 provided with a recess or passageway 36 formed in one surface thereof and 125 overlying the top wall 37 of the guide or passageway 30, the construction being such that the welt 31 and reinforcing strip 38

when passed through their respective passageways or guides will be directed to the fastening inserting position with the reinforcing strip overlying the fastening receiving portion of the welt.

It is desirable that the inner edges of the welt and reinforcing strip shall overlie the upper and insole in substantially the same vertical plane. This permits the welt strip to be made sufficiently wide to afford a good support for the heads of the fastenings without the other edge of the strip appearing at the outer edge of the welt in the finished shoe. The welt and reinforcing guides or passageways are therefore so related that the inner guiding edges 39 and 40 thereof shall be in substantially the same vertical plane. The arm 34 is adjustably connected to the head 29 by the bolt 41 which passes through an elongated slot 42 in the arm and engages the head 29 which permits relative movement of the guides or passageways to bring them into the desired relation.

In some cases it may be expedient to direct the welt reinforcing strip in its passage from the supply or reel 32 to its guide, and in such cases an arm 43 having a strip engaging and directing end 44 may be supported by the bracket 33, Fig. 1.

About the toe and in the shank of the shoe, the welt has a tendency to curl over or bend either upwardly or downwardly, at its projecting outer edge portion as it is being secured to the upper and insole, and the location of the welt with relation to the upper and insole is liable to vary. Accordingly the invention comprises a support for the projecting edge of the welt opposite the fastening inserting position and a rest against which the upper of the shoe may bear. This rest is preferably formed as a roller upon the top portion of which the projecting outer edge of the welt may be sustained and against the side of which the upper of the shoe opposite the sole edge may bear. As illustrated by Fig. 5, the roller 45 is mounted upon a stud 46 carried by a slide 47, which may be secured in adjusted position by a set screw 48 passing through the slot 49 in the slide and engaging a support connected to the head frame or other sustaining means. The roller 45, in the present instance, is frusto-conical in peripheral outline as indicated in Fig. 5, and is received in a seat 51 formed in the support 50, the construction being such that the edge portion of the roller may project beneath the outer edge portion of the welt and support it, while the face of the roller bears against the shoe upper opposite the edge of the insole.

As the welt and reinforcing strip are separately guided to the fastening inserting mechanism their lateral position relative to the upper and edge of the insole is deter-

mined by the two guides or passageways 30 and 36 respectively, and as the shoe is fed by the awl fresh supplies of welt and reinforcing strips are drawn therethrough. There is necessarily a short distance between the delivery portions of the guides or passageway and the fastening inserting position due to the throat 16, against the lower surface of which the work is clamped by the horn during the fastening inserting operation, and as the work is fed by the awl the horn drops slightly as usual to permit the work to be fed. At this time the welt and reinforcing strip are free between their respective guides and the awl which is then in the work and the lateral position of the welt and reinforcing strip is apt to vary with relation to the inserting mechanism. To prevent this an edge gage is provided, preferably one at each edge of the welt, opposite or at each side of the fastening inserting position. These gages for insuring the lateral position of the welt and consequently that of the reinforcing strip, at the fastening inserting position may be variously formed, and in the present instance of the invention the gage for the outer or projecting edge of the welt is afforded by the end 52 of the support 50 above the top of the roller 45, substantially as illustrated by Fig. 5. The gage for the inner edge of the welt where it overlies the upper 54 and insole 55 comprises an arm 53 adjustably secured to the head frame 2 by suitable means, such as the bolts 56, Fig. 1, the edge portion of said gage being positioned relative to the opposite edge gage 52 to cause the welt to be retained between them in proper lateral relation to the upper and insole at each side of the fastening inserting position, Fig. 5.

The operation of securing the reinforcing strip, the welt, upper and insole together by metallic fastenings passing therethrough and the action of the guiding means for directing the welt and reinforcing strip to the fastening inserting position, will be sufficiently clear from the description of the machine and its operation hereinbefore given, but briefly, it may be outlined as follows: The welt and welt reinforcing strip are separately passed through their respective guides or passageways and the end of the welt is placed upon the upper and insole of the lasted shoe sustained upon the work supporting horn with the overlying welt reinforcing strip below the fastening inserting mechanism and throat block. The horn is then raised to position the work operatively with relation to the inserting mechanism and the machine is started. The awl descends and pierces the reinforcing strip, the welt, upper and insole, and then the horn drops slightly to permit the work to be fed by the awl which while still in

the work moves in the line of feed, thus moving the shoe over the work support and drawing a fresh supply of welt and reinforcing strip from their respective sources 5 of supply. The horn then rises to again clamp the work, the awl is withdrawn and the driver inserts a fastening in the hole previously made by the awl which has been returned to initial position. As the welt and 10 reinforcing strip are drawn from the supply, they are separately guided to the fastening inserting position into overlying relation with respect to the upper and insole. The projecting edge of the welt is supported 15 upon the top surface of the roller and its lateral position with relation to the inserting mechanism insured during the feed and while the fastenings are being inserted. The fastenings are preferably driven through 20 the work and the penetrating ends thereof are clenched or turned upward into the insole below the reinforcing strip by the horn.

Having thus described my invention, I claim as new and desire to secure by Letters 25 Patent of the United States:

1. In a machine for attaching a welt to a lasted shoe, the combination of fastening inserting mechanism, a welt guide for directing the welt to the fastening inserting position, a guide for separately directing welt reinforcing material on to the welt at the fastening inserting position to prevent the head of the fastening when driven from penetrating the welt, and means for operating 30 the fastening inserting mechanism for driving a fastening into the reinforcing material, the welt, upper, and insole.

2. In a machine for attaching a welt to a lasted shoe, the combination of fastening 40 inserting mechanism, a guide having a passageway for directing the welt to the fastening inserting position, and a passageway for separately directing welt reinforcing material on to the welt with the inner edges 45 of the welt and reinforcing material in the same vertical plane overlying the insole, and means for operating the fastening inserting mechanism to cause a fastening to be driven into the reinforcing material, the welt, upper and insole to unite said parts.

3. In a machine for attaching a welt to a lasted shoe, the combination of a shoe supporting horn engaging the inside of the insole of a shoe, fastening inserting mechanism, a stationary guide having a passageway for directing the welt to the fastening inserting position, and a passageway for separately directing a welt reinforcing strip on to the welt at the fastening inserting position, and means for operating the fastening inserting mechanism to cause a fastening to unite the reinforcing strip, the welt, upper, and insole and be clenched below the reinforcing strip.

4. In a machine for attaching a welt to a lasted shoe, the combination of a work supporting horn, fastening inserting mechanism, a stationary guide having a passageway for directing the welt to the fastening inserting position above the insole, and a 65 passageway for separately directing a welt reinforcing strip on to the welt at the fastening inserting position to prevent the head of a fastening from passing through the welt as it is driven, means for operating 70 the fastening inserting mechanism to drive a fastening into the reinforcing strip, the welt, upper and insole, and means for moving the fastening inserting mechanism to feed the work and draw a fresh supply of 75 the welt and the reinforcing strip through the stationary guide.

5. In a machine for attaching a welt to a lasted shoe, the combination of fastening inserting mechanism, a welt guide for directing the welt to the fastening inserting position, a guide for separately directing a welt reinforcing strip on to the welt above the 85 insole, a roller having a surface for supporting the projecting outer edge portion of the 90 welt and bearing against the upper below the welt, and means for operating the fastening inserting mechanism to cause a fastening to be driven into and to unite the 95 welt reinforcing strip, the welt, upper and insole.

6. In a machine for attaching a welt to a lasted shoe, the combination of fastening inserting mechanism, guiding means having a passageway for directing the welt to the 100 fastening inserting position and a passageway for separately directing a welt reinforcing strip on to the welt with the inner edges of the welt and reinforcing strip in the same vertical plane overlying the insole, 105 a roller having a surface for supporting the edge of the welt projecting beyond the reinforcing strip, and means for operating the fastening inserting mechanism for driving a fastening into the reinforcing strip, the 110 welt, upper, and insole.

7. In a machine for attaching a welt to a lasted shoe, the combination of a work supporting horn, fastening inserting mechanism, means for guiding a welt into overlying relation to the upper and insole of a lasted shoe supported by the horn, means for separately guiding a welt reinforcing strip on to the welt at the fastening inserting position with the inner edges of the 115 welt and reinforcing strip in the same vertical plane overlying the upper and insole, a roller for supporting the projecting outer edge of the welt opposite the fastening inserting position, and means for operating 120 the fastening inserting mechanism.

8. In a machine for attaching a welt to a lasted shoe, the combination of a work sup-

porting horn for engaging the inside of the insole of a lasted shoe, fastening inserting mechanism, means for guiding a welt into overlying relation with the upper and insole of a shoe on said horn, means for separately guiding a welt reinforcing strip on to the welt at the fastening inserting position, means for guiding the edges of the welt at opposite sides of the fastening inserting position, and means for operating the fastening inserting mechanism to drive a fastening into the reinforcing strip, the welt, upper and insole.

9. In a machine for attaching a welt to a lasted shoe, the combination of a work supporting horn for engaging the inside of the insole of a lasted shoe, fastening inserting mechanism, means for guiding a welt into overlying relation with the upper and insole of a shoe on said horn, means for separately guiding a welt reinforcing strip on to the welt at the fastening inserting position, means for supporting the projecting portion of the welt, an edge gage for guiding the outer edge of the welt opposite the fastening inserting position, and means for operating the fastening inserting mechanism to drive a fastening into the reinforcing strip, the welt, upper and insole.

10. In a machine for attaching a welt to a lasted shoe, the combination of a work supporting horn, fastening inserting mechanism, means for guiding a welt into overlying relation with the upper and insole of a shoe supported on the horn, means for separately guiding a reinforcing strip on to the welt at the fastening inserting position, means for feeding the work and drawing a fresh supply of welt and reinforcing strip from their source of supply, edge gauges acting on the edges of the welt adjacent the fastening inserting position to maintain the lateral relation of the welt with the upper and insole as the work is fed and while a fastening is being driven, and means for operating the fastening inserting mechanism to drive a fastening into the reinforcing strip, the welt, upper and insole.

11. In a machine for attaching a welt to a lasted shoe, the combination of a work supporting horn, fastening inserting mechanism, means for guiding a welt into overlying relation with the upper and insole of a shoe on said horn, means for separately guiding a welt reinforcing strip on to the welt at the fastening inserting position, a roller for supporting the projecting edge of the welt, an edge gage above the roller for guiding the edge of the welt supported by said roller, and means for operating the fastening inserting mechanism to drive a fastening into the reinforcing strip, the welt, upper and insole.

12. In a machine for attaching a welt to

a lasted shoe, the combination of a work supporting horn, fastening inserting mechanism, a guide for directing the welt into overlying relation with the upper and insole of a shoe on said horn, a guide for separately directing a reinforcing strip on to the welt at the fastening inserting position, means for effecting combined and separate adjustment of said guides to position the welt with relation to the upper and insole of the shoe on said horn and the reinforcing strip with relation to the welt, and means for operating the fastening inserting mechanism to drive a fastening into the reinforcing strip, the welt, upper and insole.

13. In a machine for attaching a welt to a lasted shoe, the combination of a work supporting horn, fastening inserting mechanism, means for guiding a welt into overlying relation with the upper and insole of a shoe on said supporting horn, means for guiding a welt reinforcing strip on to the welt at the fastening inserting position, a frusto-conical roller having a flat top surface for supporting the projecting edge of the welt and engaging the upper of the shoe on said horn, and means for operating the fastening inserting mechanism to drive a fastening into the reinforcing strip, the welt, upper and insole.

14. A machine for attaching a welt to a lasted shoe, comprising a work support, fastening inserting mechanism, guiding means for a welt and a separate welt reinforcing strip provided with a lower passageway for the welt and an upper passageway for the reinforcing strip, means for securing the guiding means in position to direct the welt and reinforcing strip into overlying relation with the upper and insole of a shoe on said horn, and means for operating the fastening inserting mechanism to drive a fastening into the reinforcing strip, the welt and insole.

15. In a machine for attaching a welt to a lasted shoe, the combination of a work supporting horn, fastening inserting mechanism, a guide having a passageway for directing the welt into overlying relation with the upper and insole of a shoe on said support, and a passageway for directing a reinforcing strip on to the welt at the fastening inserting position, a guide between the passageway for the reinforcing strip and its source of supply to direct the reinforcing strip to said passageway, and means for operating the fastening inserting mechanism to drive a fastening into said reinforcing strip, the welt, upper and insole to unite them.

16. In a machine for attaching a welt to a lasted shoe, the combination of a work supporting horn, fastening inserting mechanism, guiding means for separately guiding

a welt and a welt reinforcing strip in over-
lying relation to the upper and insole of a
shoe on said supporting horn, comprising
an arm having a head provided with a pas-
sageway for the welt, an arm having a head
provided with a recess in one face and over-
lying the top wall of the welt passageway,
means for adjustably securing said arms in
relative position to direct the welt reinforce-

ing strip on to the welt at the fastening in- 10
serting position, and means for operating
the fastening inserting mechanism to drive
a fastening into the reinforcing strip, the
welt, upper and insole.

In testimony whereof I have signed my 15
name to this specification.

GEORGE GODDU.
